DESIGN FOR A RING BOX OR THE LIKE

William Ludel, Brooklyn, N. Y., and Edward Goldstein, Brookline, Mass., assignors to Louis A. Roselaar, New York, N. Y., a partnership composed of William Ludel, Jacob Ludel, and Louis A. Roselaar

Application March 11, 1944, Serial No. 112,870

Term of patent 14 years

(Cl. D80—5)

To all whom it may concern:

Be it known that we, William Ludel and Edward Goldstein, both citizens of the United States and residents, respectively, of Brooklyn, in the county of Kings and State of New York, and Brookline, in the county of Suffolk and State of Massachusetts, have invented a new, original, and ornamental Design for a Ring Box or the like, as shown, of which the following is a specification, reference being had to the accompanying drawing, forming a part thereof.

We claim:

The ornamental design for a ring box or the like, as shown.

WILLIAM LUDEL.
EDWARD GOLDSTEIN.
